The Pullman Company, Chicago, Ill., a corpora-
tion of Illinois

Application March 8, 1941, Serial No. 382,306

7 Claims. (Cl. 228—48)

A new type of sleeping car known as the coach sleeper has recently been introduced to the traveling public. This car is equipped with a plurality of rooms, each of which is suitable for accommodating three or six occupants, depending upon the size of the room. Each room is provided with a seat and a berth for each occupant, and additional equipment, including a wash basin, furnishing all possible conveniences to the passengers for both day and night travel.

The berths are arranged in tiers of three, and there is ample space between the berths in each tier to make the sleeping accommodations sufficiently roomy and ideally comfortable.

Suitable means are furnished to close off each room from the remainder of the car, so as to provide adequate privacy to its occupants to permit their using the room floor area for standing room while they are dressing and undressing and making their toilet at bed time and upon rising in the morning.

Access to the intermediate and upper berths is made convenient by a novel ladder, which is placed in position for use only when the berths are made up for occupancy and is stored in an out-of-the-way place during the daytime when the room is in condition for day use. This ladder forms the subject matter of the present invention.

One of the principal objectives in the minds of those designing the coach sleeper was to arrange the car so that it could comfortably accommodate the maximum possible number of occupants, both for day and night travel, giving each occupant adequate room and everything essential to assure him of a comfortable trip. Because of the limited space available in the car, each room necessarily is made no larger than is absolutely necessary for the intended purposes. The floor space in each room is ample for all practical purposes, but it is essential that it be kept free from permanent obstructions both in the daytime and at night, so that this area can be made available for use by the room occupants.

The ladder, when it is in position to give access to the upper berths, must not permanently clutter the floor area, but is disposed to render the floor area available for standing room to those who wish to use it.

Among the principal objects of the present invention, then, are the following:

To provide a safe, convenient ladder giving ready access to the upper berths, and one which is light in weight and easy to handle; to provide means for supporting the ladder in its position for use; which makes the ladder sturdy and yet

simple to install and remove, so as not to require too much of the porter's time when making the room up for day or night use; to provide a ladder assembly which permits the ladder very easily and safely to be moved out of the way to clear the floor space for use by any of the occupants with means for holding the ladder in this inoperative position; and to provide a convenient space for storage of the ladder without utilizing any of the revenue earning space in the car.

The above constitutes some of the principal objects and advantages of the present invention, others of which will become apparent from the following description and the drawings, in which

Fig. 1 is a front elevational view of a preferred embodiment of the invention showing the ladder installed in position for giving access to the intermediate and upper berths, and is shown as it is applied to a six-occupant room;

Fig. 2 is a fragmentary front elevational view of the ladder shown applied to a three-occupant room;

Fig. 3 is an end elevational view of the ladder in place for use and shows in broken lines the ladder swung back against the berths so as to clear the floor area in the room;

Fig. 4 is a top plan view of the ladder taken on the line 4—4 of Fig. 3;

Fig. 5 is a sectional view taken on the line 5—5 of Fig. 3;

Fig. 6 is an enlarged detail view of the lower ladder support;

Fig. 7 is an enlarged detail view in side elevation showing the lower ladder support with the ladder in its operative position to give access to the upper berths;

Fig. 8 is a view corresponding to Fig. 7, but showing the ladder swung back against the berths;

Fig. 19 is a vertical longitudinal sectional view taken through one of the six-occupant rooms, showing the three berths in position for night use, with the ladder in place and looking toward the window side of the room;

Fig. 20 is a perspective view of the modified form of the ladder used for providing access to the upper and intermediate berths;

Fig. 21 is a detailed view of the top pivot and stop used in conjunction with this modified form of ladder;

Fig. 22 is an enlarged detail view of the extension mechanism on this modified form of ladder, the view being taken on the line 22—22 of Fig. 20;

Fig. 23 is a horizontal sectional view taken on the line 23—23 of Fig. 22;

Fig. 24 is an enlarged vertical sectional view taken through the room floor showing the lower pivot for the ladder; and

Fig. 25 is a front elevational view of the top portion of the ladder showing the top pivot and the stop.

This application is a continuation in part of the copending application of Peter Parke, James K. Tully, Leif Andersen and Basil E. Jones, Serial No. 348,670, filed July 31, 1940.

Specific embodiments of the present invention are selected for the purpose of complying with section 4883 of the Revised Statutes. As shown, the ladder is used in conjunction with berths arranged in tiers of three, but, obviously, it can be used in any other arrangement of berths in which there is at least one berth at a level high enough to require the use of a ladder. Obviously, many modifications may be made in the embodiments disclosed herein without departing from the scope of the present invention.

The ladder forming the subject matter of the present invention is sturdy when in position for use and is very conveniently located to make the ascent and descent to and from the upper and intermediate berths safe and easy. This ladder is in place for use throughout the entire night, so as not to require the services of the porter in the event an occupant of an upper or intermediate berth wishes to descend, and it is so arranged that it can be moved readily out of the way of those persons using the floor area in the room. In the daytime, the ladder is conveniently stored in an out-of-the-way place behind one of the seats.

For the purpose of illustrating the ladder as it is employed in a coach sleeper, enough of the car with its equipment is shown to bring out the relationship between the ladder and the car equipment.

The preferred form of the ladder forming the

subject matter of the present invention is shown in Figs. 1 to 13, inclusive. Referring particularly to Fig. 1, the ladder is generally indicated at 129, and comprises a pair of spaced side pieces 130 and 131 connected by a plurality of vertically arranged rungs or steps 132. In Fig. 1, the ladder is shown applied to a six-occupancy room in which are oppositely disposed lower, intermediate and upper berths 87, 89, and 88, respectively, between which the ladder 129 is mounted.

The lower berth 87 is a convertible sofa comprising a seat portion 128 and a back or berth portion 239, the former of which, when in its horizontal position shown in Fig. 1, supports a mattress (not shown) and forms the berth.

At the lower and upper ends of the side piece 131 of the ladder 129 are fulcrums 133 and 134, which are horizontally offset from each other and about which the ladder pivots from an inclined operative position shown in Fig. 1 to an inoperative position shown in broken lines in Fig. 3. Stops, generally indicated at 135 and 136 at the top and bottom, respectively, of the side piece 130, help support the ladder in its operative position.

The lower fulcrum 133 (Figs. 1, 10, and 11) comprises a female bracket 137 mounted on the seat portion 128 of the lower berth or sofa 87 and a male portion or trunnion member 138 secured to the bottom of the ladder at the lower end of the ladder side piece 131.

The male portion 138 comprises an angle member 139 below which projects a boss 140, which is adapted to fit into the female slot 141 of the female bracket 137. A pair of lugs 142 extend radially outwardly from the sides of the boss 140.

The female bracket 137 comprises a horizontal portion 143 and a projection 144 providing the female slot 141. The upper surface 145 surrounding the female slot 141 is inclined from the horizontal, as best shown in Fig. 11, and a pair of radially disposed indentations 146 are provided in this inclined surface 145. These indentations are arranged to receive the lugs 142 when the trunnion member is in place in its female portion and the ladder is swung back against the berths 87, 89, and 88 to its inoperative position.

As best shown in Fig. 7, the lugs 142 are supported on the upper inclined surface 145 when the ladder is in its operative position. During movement of the ladder from the operative position to its inoperative position shown in Fig. 8 and in broken lines in Fig. 3, the lugs 142 ride on the inclined surface 145 until the ladder is swung back against the berths, as shown in broken lines in Fig. 3, in which position the lugs 142 are seated in the indentations 146, as best shown in Fig. 8. In this position, the ladder is held against the berths by the cooperation between the lugs and the indentations.

At the top of the ladder adjacent to the side piece 131 is a female bracket 147 (Fig. 1) attached to the outer edge of the upper berth 88 and extending outwardly therefrom. An upper trunnion 148 is secured to the side piece 131 and cooperates with the bracket 147 to form the upper pivot of the ladder.

Referring particularly to Figs. 4 and 9, the upper female bracket 147 comprises a horizontally extending portion 147', at the rear edge of which is a flange 149 by which the bracket is secured to the edge of the berth 88, and at the forward end of which is a curved member 150 forming a slot 151. The curved member 150 terminates at 152 in spaced relation to the end 75 of the horizontal portion 147' of the bracket to

form an opening 153. A spring bracket pin 154 extends from the end of the horizontal portion 147' of the bracket into the slot 151 and partially closes the opening 153. This pin 154 passes through an opening in the end 155 of the horizontal portion 147' of the bracket and is guided by guide members 156 and 157 in the horizontal portion 147' of the bracket. The pin 154 has a shank 158 of a lesser diameter than the pin, about which is placed a coil compression spring 159, which is seated between the guide 157 and a shoulder 160 formed at the rear edge of the pin 154. This spring urges the pin 154 outwardly to partially close the opening 153 in the slot 151, as shown in Fig. 9. A slot 161 in web 162 of the horizontal portion 147' of the bracket receives a lug 163 projecting downwardly from the pin 154 through the slot 161 so that the travel of the pin 154 is limited by the restricted travel of the pin 163 in the slot 161. Pin 163 also serves as a release knob (Fig. 1) which can be manipulated by hand to force the pin 154 back into the horizontal portion 148 of the bracket 147 against the force of spring 159 to clear the opening 153 in slot 151.

Referring to Fig. 1, the upper trunnion member 148 fits into the female slot 151 of the upper bracket 147, and, when it is in place, the pin 154 partially closes the opening 153 behind the trunnion member 148 to lock it in place.

The ladder 129 is portable and is installed only when the berths are made up for occupancy. When installing the ladder for use, the lower trunnion 138 is inserted in the female bracket 137. The pin 154 in the upper bracket 147 is forced back to clear the opening 153 (Fig. 9), and then the upper trunnion member 148 is passed through this opening 153 into the slot 151. The pin 154 is then allowed to return to its normal position to partially close the opening 153 and lock the trunnion member 148 in place. The ladder is thereby supported between the lower and upper berths, and its installation is completed simply and requires only a negligible amount of time.

The stops 135 and 136 (Fig. 1) at the upper and lower extremities of the ladder adjacent to the side piece 130 are mounted on the upper and lower berths 88' and 87', respectively, and they are aligned with the brackets 137 and 147 so that the ladder 129, when in its operative position, assumes a right angle relationship with the general plane of the berths. The upper stop 135 is best shown in Fig. 4. A rubber bumper 164 is placed on the upper extremity of the side piece 130, and it engages the outer edge of the upper stop 135 to form a cushion between the ladder and the stop.

The lower stop 136 is best shown in Figs. 1, 5, 12, and 13, and comprises a channel shaped member 165 having an end piece 166 (Fig. 13). This member is secured to the lower berth 87' and is so arranged that a horizontal projection 167 (Fig. 1) of the ladder rests against the end 166 of the member 165. A rubber bumper 168 is mounted on the ladder, and it engages the end 166 of the stop member 165 to form a cushion.

Referring again to Fig. 11, as previously explained, the top surface 145 of the projection of the female bracket is inclined. As the ladder is rotated from its operative to its inoperative position, the lugs 142 (Figs. 7 and 10) on the lower trunnion of the ladder ride up this inclined surface. The weight of the ladder lowers the lugs 142 into the indentations 146, and when the lugs

are in this position the ladder is locked in its inoperative position. To unlock the ladder and to return it to its operative position, one need merely grasp the side piece 130 of the ladder and rotate it toward the stops 135 and 136. Only a slight force is required to raise the lugs 142 out of the indentations 146. The inclination of the top surface 145 on the female bracket tends to urge the ladder toward its operative position at all times when the lugs 142 are supported on the inclined surface out of their seated position in the indentations 146.

In a three-occupancy room, there is only one bank of berths and the room is correspondingly narrower. In this condition, the ladder when in its operative position spans the space between the berths and the opposite room partition 84 (Fig. 2). The ladder is mounted in exactly the same manner as previously described, but in this instance the stops 135 and 136 are mounted directly on the partition 84.

A modified form of ladder is shown at 353 in Figs. 14 to 25, inclusive. This ladder comprises a pair of spaced side members 354 and 355, to which are secured steps 356. An extension member 357 is adjustably secured to the ladder, and, when the ladder is not in use, this member is lowered against the top of the ladder in the position shown in dotted lines 358 in Fig. 20.

The extension member 357 comprises a pair of rods 359 and 360, connected at the top by a U-shaped member 361 having upwardly extending arms 362 and 363 with a reinforcing member 364 connecting arms 362 and 363 slightly below their free ends. To the front edge of the upper berth 88 (Figs. 14 and 20) a bracket 365 is secured having an outwardly extending projection 366 on the end of which is a socket 367 adapted to receive the free end of arm 362 of the ladder extension 357. A fiber bushing 367' lines the inner surface of the socket 367 to prevent rattling.

At the lower end of ladder side 355 is a pivot member 368 having a downwardly extending male portion 369 adapted to fit into the female portion 370 (Figs. 19 and 24), recessed into the car floor 51.

On the front edge of the second upper berth (in this instance, referred to as 88' in Fig. 20) in the six-occupant room is attached a ladder stop 371, against which the upwardly extending arm 363 of ladder extension 357 rests when the ladder is being supported in its operative position. The upper end of arm 363 may be padded at 390, where it engages the ladder stop 371, so as to eliminate noise. Stop 371 (Fig. 25) is applied to the partition wall across from the berths in the case of the three-occupant rooms. Also, in the case of the three-occupant rooms, the ladder extension rod 359 is straight to the end thereof.

When the ladder is in position for use, it assumes the position shown in Fig. 14, obstructing the floor area for anyone attempting to use the toilet facilities. A person desiring to use the floor area or the toilet facilities merely rotates the ladder against the berths about the socket 367 and pivot point 368 at the top and bottom, respectively, of the ladder, as shown in dotted lines 372 in Fig. 18, thereby placing the ladder out of the way. In this manner, the ladder may very readily be placed in position for persons desiring to ascend or descend from the intermediate or upper berths, and yet may be moved out of the way of those persons desiring to use the floor area.

The adjustable extension member 357 at the top of the ladder is lowered to the dotted line position 358 (Fig. 20) when there is no further use for the ladder and it is to be placed in storage. Rods 359 and 360 pass through collar members 373 and 373', respectively (Fig. 19), the latter of which are attached to the sides 355 and 354, respectively, of the ladder by brackets 374, which are screwed to the ladder as best shown in Figs. 20 and 23.

Referring to Fig. 22, the collar member 373 surrounds the rod 359, and adjacent to the lower end of collar 373 is a notch 375. A block 376 is inserted in the hollow rod 359 and is held in place by a screw 377. Directly below the block 376 a spring 378 is pivoted to the rod 359 at 379, so that the spring 378 pivots about a horizontal axis. One arm 380 of spring 378 extends upwardly and is held by block 376, as best shown in Figs. 22 and 23. The other arm 381 of spring 378 extends downwardly from the pivot point 379, and engages a latch member 382 pivoted at 383 to the rod 359. The lower end of arm 381 of the spring 378 is secured to the latch member 382. The latch 382 projects forward at 384 and protrudes beyond the periphery of rod 359 through a slot 385 in the rod. A fiber bushing 386 is inserted between the rod 359 and the collar 373 adjacent to the lower end of the collar, and a similar bushing 386' is placed between the rod 359 and the collar 373' adjacent to the top of the collar. These bushings provide a tight fit and prevent rattling of the ladder parts.

Latch 382 locks the extension member 357 in raised position by means of the protruding member 384 of the latch extending into slot 375 of the collar 373. When it is desired to lower the extension member 357, latch 382 is rotated in a clockwise direction about pivot point 383 by applying a pressure to lever 387 on the end of the latch, thereby unlocking the extension member 357 and allowing it to be lowered to the dotted line position 358 shown in Fig. 20. A nut 388 is placed over the lower end of rod 359, so as to limit the upward movement of rod 359 by abutting against the end of collar 373. A bearing member 389 is provided between the lever 387 and the nut 388 at the lower end of the assembly against which latch 382 may bear.

A pin 569 (Figs. 20, 22 and 23) passes through a slot 570 in the collar and in the rod and locks the extension member 357 in its raised position. A chain 571 secures the pin 569 to the ladder at 572. A collar 373' (Fig. 19), similar to collar 373, is located on the other side of the ladder. A plurality of openings 391 (Fig. 20) is placed in the sides 354 and 355 of the ladder to permit the ladder to be more easily grasped and to greatly lighten the weight of the ladder.

When the ladder is in place for use, as shown in solid lines in Fig. 18, the lighting fixture 101 is adapted to direct a beam of light downward onto the ladder to illuminate it for the occupant.

Referring to Figs. 15 and 16, the ladder 353 is stored behind one of the sofas 87. A bracket 578 (Figs. 15-18, inclusive) having a horizontal surface 579 across its top is secured to the room partition 84 adjacent to the floor by means of screws or rivets passing through flanges 580 and 581 at the top and bottom, respectively, of the bracket 578. The ladder 353 is placed crosswise of the car behind the sofa with the ladder rungs extending vertically, and the lower end of the ladder is supported on the housing 115 covering

the heating pipes, and the ladder adjacent to its upper end is supported on the horizontal surface 579 of the bracket 578. The sofa back 239, when in its upright position fastened against the room partition 84, holds the ladder securely against the partition and prevents rattling thereof. When it is desired to remove the ladder from its storage space, the sofa back 239 is unlatched and pivoted forward away from the wall, thereby providing access into the ladder storage space.

We claim:

1. For use in providing access to and from an upper berth in a vehicle, a ladder comprising spaced side pieces supporting a plurality of rungs, a pivot support at the bottom of one side piece including a male portion and a female portion, one of said portions being fixed on the lower end of said side piece and the other being stationarily mounted adjacent thereto, a pivot support at the top of said side piece including a male portion and a female portion, one of said portions being attached to said side piece and the other being stationarily mounted adjacent thereto and adjacent to the upper berth, said pivot supports being horizontally offset from each other, thereby mounting said side piece in an inclined position, the ladder pivotally swinging about said side piece from an inoperative position adjacent to the berth to an operative position projecting at a right angle from the berth, and means limiting the swinging movement of the other side piece for supporting the ladder in operative position.

2. For use in providing access to and from an upper berth in a vehicle, a ladder comprising spaced side pieces supporting a plurality of rungs, a pivot support at the bottom of one side piece including a male portion and a female portion, one of said portions being fixed on the lower end of said side piece and the other being stationarily mounted adjacent thereto, a pivot support at the top of said side piece including a male portion and a female portion, one of said portions being attached to said side piece and the other being stationarily mounted adjacent thereto and adjacent to the upper berth, the respective portions of each pivot support being separable from each other whereby the ladder may be removed, the stationarily mounted portions of said pivot supports being horizontally offset from each other whereby said side piece is mounted in an inclined position, and the ladder pivotally swinging about said side piece from an inoperative position adjacent to the berth to an operative position projecting at a right angle from the berth, and means limiting the swinging movement of the other side piece for supporting the latter in operative position.

3. For use in providing access to and from an upper berth in a vehicle, a ladder comprising spaced side pieces supporting a plurality of rungs, a pivot support at the bottom of one side piece including a male portion and a female portion, one of said portions being fixed on the lower end of said side piece and the other being stationarily mounted adjacent thereto, a pivot support at the top of said side piece including a male portion and a female portion, one of said portions being attached to said side piece and the other being stationarily mounted adjacent thereto and adjacent to the upper berth, the respective portions of each pivot support being separable from each other whereby the ladder may be removed, the stationarily mounted portions of said pivot supports being horizontally offset from each

other whereby said side piece is mounted in an inclined position, and the ladder pivotally swinging about said side piece from an inoperative position adjacent to the berth to an operative position projecting at a right angle from the berth, means locking the respective portions of each pivot support together, and means limiting the swinging movement of the other side piece for supporting the latter in operative position.

4. For use in providing access to and from an upper berth in a vehicle, a ladder comprising spaced side pieces supporting a plurality of rungs, a pivot support at the bottom of one side piece including a male portion and a female portion, one of said portions being fixed on the lower end of said side piece and the other being stationarily mounted adjacent thereto, a pivot support at the top of said side piece including a male portion and a female portion, one of said portions being attached to said side piece and the other being stationarily mounted adjacent thereto and adjacent to the upper berth, said pivot supports being horizontally offset from each other, thereby mounting said side piece in an inclined position, the ladder pivotally swinging about said side piece from an inoperative position adjacent to the berth to an operative position projecting at a right angle from the berth, means limiting the swinging movement of the other side piece for supporting the ladder in operative position, and means holding the ladder in inoperative position.

5. For use in providing access to and from an upper berth in a vehicle, a ladder comprising spaced side pieces supporting a plurality of rungs and including an extensible and retractable member projecting upwardly from the ladder, a pivot support at the bottom of one side piece including a male portion and a female portion, one of said portions being fixed on the lower end of said side piece and the other being stationarily mounted adjacent thereto, a pivot support at the top of said side piece including a male portion and a female portion, one of said portions being formed on said member and being thereby attached to said side piece and the other being stationarily mounted adjacent thereto and adjacent to the upper berth, said pivot supports being horizontally offset from each other, thereby mounting said side piece in an inclined position, the ladder pivotally swinging about said side piece from an inoperative position adjacent to the berth to an operative position projecting at a right angle from the berth, and means limiting the swinging movement of the other side piece for supporting the ladder in operative position, said member being retractile and extensible to engage and disengage the portions of the pivot support at the top of the first named side piece whereby the ladder may be mounted and removed.

6. For use in providing access to and from an upper berth in a vehicle, a ladder comprising

spaced side pieces supporting a plurality of rungs and including an extensible and retractable member projecting upwardly from the ladder, a pivot support at the bottom of one side piece including a male portion and a female portion, one of said portions being fixed on the lower end of said side piece and the other being stationarily mounted adjacent thereto, a pivot support at the top of said side piece including a male portion and a female portion, one of said portions being formed on said member and being thereby attached to said side piece and the other being stationarily mounted adjacent thereto and adjacent to the upper berth, said pivot supports being horizontally offset from each other, thereby mounting said side piece from an inoperative position adjacent to the berth to an operative position projecting at a right angle from the berth, means limiting the swinging movement of the other side piece for supporting the ladder in operative position, said member being retractile and extensible to engage and disengage the portions of the pivot support at the top of the first named side piece whereby the ladder may be mounted and removed, and means latching said member in its position in which the portions of said last named pivot support are engaged for mounting the ladder.

7. For use in providing access to and from an upper berth in a vehicle, a ladder comprising spaced side pieces supporting a plurality of rungs and including an extensible and retractable member telescopically mounted on the side pieces and projecting upwardly from the ladder, a pivot support at the bottom of one side piece including a male portion and a female portion, one of said portions being fixed on the lower end of said side piece and the other being stationarily mounted adjacent thereto, a pivot support at the top of said side piece including a male portion and a female portion, one of said portions being formed on said member and being thereby attached to said side piece and the other being stationarily mounted adjacent thereto and adjacent to the upper berth, said pivot supports being horizontally offset from each other, thereby mounting said side piece in an inclined position, the ladder pivotally swinging about said side piece from an inoperative position adjacent to the berth to an operative position projecting at a right angle from the berth, means limiting the swinging movement of the other side piece for supporting the ladder in operative position, said member being retractile and extensible to engage and disengage the portions of the pivot support at the top of the first named side piece whereby the ladder may be mounted and removed, and means latching said member in its extended position.
